UNITED STATES PATENT OFFICE.

VICTOR M. SUMMA AND JAMES T. ST. CLAIR, OF ST. LOUIS, MISSOURI, ASSIGNEES TO
AMERICAN CAR & FOUNDRY COMPANY, OF ST. LOUIS, MISSOURI, A CORPORATION
OF NEW JERSEY.

CAR-UNDERFRAME.

No. 893,948.

Specification of Letters Patent.

Patented July 21, 1908.

Application filed February 3, 1908. Serial No. 414,007.

To all whom it may concern:

Be it known that we, VICTOR M. SUMMA and JAMES T. ST. CLAIR, both citizens of the United States, residing at St. Louis, Missouri, have invented a certain new and useful Improvement in Car-Underframes, of which the following is a full, clear, and exact description, such as will enable others skilled in the art to which it appertains to make and use the same, reference being had to the accompanying drawings, forming part of this specification, in which—

Figure 1 is a top plan view, partly in section, of a car underframe constructed in accordance with our invention; Fig. 2 is a longitudinal sectional view of the underframe, showing the center sill in side elevation; and Fig. 3 is a cross sectional view of the underframe, the righthand half of said figure being taken adjacent the bolster and the lefthand half being taken adjacent the transverse center of the car.

This invention relates to car underframes, and has for its object to provide a trussed longitudinal sill that is strong and of lightweight.

Another object of our invention is to provide a car underframe of novel construction.

We have herein shown a car underframe having a center sill constructed in accordance with our invention but it will, of course, be understood that our improved sill could be used as the side sill of an underframe instead of as a center sill.

Referring to the drawings which illustrate the preferred form of our invention, 1 designates the compression member of our improved sill which preferably consists of a channel that extends from bolster to bolster of the underframe, said channel being arranged with its side flanges or legs projecting downwardly, as shown in Fig. 3. The tension member of the sill also consists of a channel iron 2 arranged with its side legs or flanges projecting downwardly and extending from bolster to bolster, said tension member lying in the same vertical plane as the compression member. Struts are interposed between said compression and tension members to produce a long deep girder, said struts consisting of a number of pairs of vertically disposed members 3, preferably angles, that are arranged outside of the side flanges of the tension and compression members 1 and 2

with one leg or flange projecting laterally 55 therefrom.

Pairs of oppositely inclined diagonal struts 4 are arranged between the vertical struts 3 and are connected at their opposite ends to gusset plates 1^a and 2^a secured to the side flanges or legs of the compression and tension members 1 and 2, respectively, the lower ends of the vertical struts 3 also being connected to the gusset plates 2^a on the tension member. Some of the vertical struts 3 are connected at their upper ends to separate gusset plates 1^b secured to the side flanges of the compression member, as shown in Fig. 2, and the other vertical struts are connected at their upper ends to straps 1^c which pass 70 over the compression member 1 of the center sill, as shown in Fig. 3. The inclined struts 4 can either be formed from commercially rolled angles or flat bars, the construction herein shown comprising both angles and flat bars. Preferably, reinforcing plates 5 are secured to the webs of the compression and tension members throughout a portion of their length to strengthen same. A longitudinal sill of this construction is strong and 80 light and can be manufactured at a low cost so that it forms a very efficient center sill for the underframe of a car.

The bolsters of the underframe each consists of a pair of parallel channels 6 arranged 85 with their horizontal legs projecting in opposite directions and extending from side sill to side sill of the underframe, the side sills 7 also consisting of channels arranged with their horizontal legs projecting outwardly, 90 as shown in Fig. 3.

Hexagonal top and bottom cover plates 8 are secured to the horizontal flanges of the bolster channels 6 and the ends of the trussed center sill project between these cover plates 95 and also between the horizontal legs or flanges of one channel of each bolster, the tension and compression members 1 and 2 being connected together at the ends of the sill by web plates 9. The outer end of each 100 of the web plates 9 is provided with an integral flange 9^a, as shown in Fig. 1, that is secured to the web of the adjacent bolster channel and the connection between the center sill and bolster is further strengthened by 105 means of angle-shaped members 10 connected to the web of the bolster channel and to the inside faces of the web plates 9, as shown

in Fig. 1, and also by means of short pieces 11 of angle iron secured to the outside faces of the web plates 9 and to the bottom cover plate 8 of the bolster, as shown in Fig. 2.

5 The draft sills 12 consist of channels that are connected to the channel-shaped end sill 13 and to the bolster, and diagonal braces 14 are arranged between the bolster and end sill, as shown in Fig. 1. The cross-bearers of the 10 underframe consist of deep channels 15 and comparatively shallow channels 16 connected at their opposite ends to the side sills and also secured to the laterally projecting flanges of the vertical struts 3 of the center 15 sill.

Having thus described our invention, what we claim as new and desire to secure by Letters Patent is:

1. A longitudinal sill for a car underframe, 20 consisting of channel-shaped tension and compression members having their webs arranged horizontally, and struts interposed between said members; substantially as described.

25 2. A longitudinal sill for a car underframe, comprising a channel-shaped tension and compression member having their webs arranged horizontally and their side legs or flanges projecting in the same direction, 30 and struts interposed between said members and connected thereto; substantially as described.

3. A longitudinal sill for a car underframe, 35 consisting of channel-shaped tension and compression members arranged with their side legs or flanges projecting downwardly, and struts interposed between said members and connected thereto; substantially as described.

40 4. A longitudinal sill for a car underframe, comprising channel-shaped tension and compression members having their webs arranged horizontally, vertically disposed struts interposed between said members, and oppositely inclined diagonal struts arranged between the vertically disposed struts and secured to said members; substantially as described.

45 5. A longitudinal sill for a car underframe, 50 consisting of channel-shaped tension and compression members, and pairs of struts connected to the side flanges of said members; substantially as described.

60 6. A longitudinal sill for a car underframe, 55 comprising channel-shaped tension and compression members having their webs arranged horizontally, pairs of vertically disposed struts connected to the side flanges of said members, and oppositely inclined diagonal struts connected to the side flanges of said members and arranged between the vertical struts; substantially as described.

65 7. A longitudinal sill for a car underframe, 60 comprising channel-shaped compression and tension members having their webs ar-

ranged horizontally, gusset plates secured to the side flanges of said members, and pairs of struts connected to said gusset plates; substantially as described.

8. A longitudinal sill for a car underframe, 70 comprising channel-shaped tension and compression members having their webs arranged horizontally, vertically disposed struts having their upper ends secured to the compression member, gusset plates connected to the tension member and having the lower ends of said struts secured thereto, and oppositely inclined diagonal struts arranged between the vertical struts and connected at their lower ends to the gusset plates on the 75 tension member; substantially as described.

9. A longitudinal sill for a car underframe, 80 consisting of channel-shaped tension and compression members having their side flanges projecting downwardly, struts interposed between said members, and straps passing over the web of the compression member and having the upper ends of some of said struts secured thereto; substantially as described.

90 10. A longitudinal sill for a car underframe, 95 comprising channel-shaped tension and compression members having their webs arranged horizontally, struts connected to the side flanges of said members, and reinforcing plates secured to the webs of said members to strengthen same; substantially as described.

11. A longitudinal sill for a car underframe, 100 comprising channel-shaped tension and compression members having their webs arranged horizontally, web plates secured to the side flanges of said members adjacent the ends of same, and pairs of vertically disposed struts and oppositely inclined diagonal struts 105 connected to the side flanges of said members between their opposite ends; substantially as described.

12. A car underframe comprising bolsters, 110 a trussed center sill arranged between said bolsters and consisting of a tension member and a compression member of channel-shape in cross section and having their webs arranged horizontally, struts interposed between said members, and web plates secured 115 to the side flanges of said members adjacent their opposite ends and also being connected to the bolsters; substantially as described.

13. A car underframe comprising a bolster, 120 a trussed center sill comprising tension and compression members and struts interposed between same, web plates secured to the tension and compression members adjacent the end of the sill, and integral flanges 125 on said web plates that are connected to the bolster; substantially as described.

14. A car underframe comprising a bolster which consists of parallel channels and top and bottom cover plates secured to the 130

- horizontal legs thereof, a trussed center sill consisting of compression and tension members and interposed struts, web plates secured to one end of said sill and provided 5 with integral flanges that are connected to the web of one channel of the bolster, angle-shaped members secured to said channel and to said web plate, and means for securing said web plates to the bottom cover plate of 10 the bolster; substantially as described.
15. A car underframe, comprising bolsters, end sills, draft sills interposed between the bolsters and end sills, a trussed center sill consisting of channel-shaped tension and compression members terminating inside of 15 the bolsters and having their webs arranged horizontally, struts interposed between said members, and means for connecting the end portions of said members to the bolsters; substantially as described.
- 20 16. A car underframe comprising side sills, a trussed center sill provided with vertically disposed struts having laterally projecting flanges, and continuous cross-bearers 25 arranged in approximately the same hori-

zontal plane as the side sills and connected at their opposite ends to the side sills, said cross-bearers being secured to the flanges on said struts; substantially as described.

17. A car underframe, comprising bolsters, 30 side sills, a trussed center sill having its opposite ends connected to the bolsters and consisting of a tension member, a compression member, and vertically disposed angle-shaped struts connected to said members, 35 and continuous channel-shaped cross-bearers connected at their opposite ends to the side sills and secured intermediate their ends to the flanges on the struts of the center sill, said cross-bearers lying in approximately the 40 same horizontal plane as the side sills; substantially as described.

In testimony whereof, we hereunto affix our signatures in the presence of two witnesses, this first day of February, 1908.
